(57) **CLAIM**

(21) Appl. No.: **29/120,791**

The ornamental design for a light cover with faux alabaster appearance, as shown and described.

(22) Filed: **Mar. 27, 2000**

DESCRIPTION

(51) LOC (7) Cl. **26-99**

FIG. 1 is a side view of a light cover with faux alabaster appearance;

(52) U.S. Cl. **D26/128**

FIG. 2 is a top view thereof; and,

(58) Field of Search D26/128-137, D26/118, 123, 127; 362/326, 329, 334, 335, 340, 351, 352

FIG. 3 is a bottom view thereof.

(56) **References Cited**

The glass of the cover is translucent, with irregular swirls formed by lines which are more opaque than intervening regions, creating an appearance similar to alabaster.
